U.S. Appl. No. 29/524,322, filed Apr. 20, 2015, entitled "Leg Rigging Clip".

Primary Examiner — Charles Hanson

(74) *Attorney, Agent, or Firm* — Fitch, Even, Tabin & Flannery LLP

(57) **CLAIM**

We claim the ornamental design for a leg rigging clip, as shown and described.

DESCRIPTION

FIG. 1 is a perspective view of a leg rigging clip in accordance with a first embodiment of our new design; FIG. 2 is a front elevational view of the leg rigging clip thereof, the rear elevational view being a mirror image thereof;

FIG. 3 is a bottom plan view of the leg rigging clip thereof; FIG. 4 is a top plan view of the leg rigging clip thereof; FIG. 5 is a right side elevational view of the leg rigging clip thereof;

FIG. 6 is a left side elevational view of the leg rigging clip thereof;

FIG. 7 is a perspective view of a leg rigging clip in accordance with a second embodiment of our new design; FIG. 8 is a front elevational view of the leg rigging clip thereof, the rear elevational view being a mirror image thereof;

FIG. 9 is a bottom plan view of the leg rigging clip thereof; FIG. 10 is a top plan view of the leg rigging clip thereof; FIG. 11 is a right side elevational view of the leg rigging clip thereof; and,

FIG. 12 is a left side elevational view of the leg rigging clip thereof.

The broken lines depict unclaimed environmental subject matter and form no part of the claim.
